RAILWAY CAR

Edward W. Dart, Dearborn, Mich., assignor to
Pullman-Standard Car Manufacturing Company, a corporation of Delaware

Application July 7, 1934, Serial No. 734,177

9 Claims. (Cl. 20—19)

The invention relates particularly to the door opening of a railway car, and to the closure therefor; its objects being to provide for the sliding movement of the door into and out of the opening and along the inner face of the car wall. Other improvements in connection with such doors and openings will be pointed out in the following specification.

In the accompanying drawings showing an embodiment of the invention

Fig. 1 is a detail side elevation of a car body; Fig. 2 is a sectional view on the line 2—2 of Fig. 1;

Fig. 3 is a fragmentary vertical sectional detail on the broken line 3—3 of Fig. 1;

Fig. 4 is a detail side elevation of the car side with the door open, some parts being broken away;

Fig. 5 is a plan section on the line 5—5 of Fig. 1; and

Fig. 6 is an inverted plan section on the line 6—6 of Fig. 1.

The invention appertains to a car of the so-called streamline type, in which the conventional form is departed from with view to lessening air resistance to the movements of the car, and with view, also, to maintaining adequate strength while securing a great reduction in weight from prevailing practice.

In attaining these advantages improvements in various details of the car have been made in addition to its general reorganization. The provision of a suitable door opening and closure therefor constitutes one of such details.

The form of the rear end of the car is shown in Fig. 1, its framing being indicated in various figures. The improved door is shown at 20, and comprises a skeleton frame 21 of tubing, portions of which appear in Figs. 2, 3 and 6, covered by sheet metal and glazed, as indicated in the figures.

The door shown is for the vestibule of a car, a section 22 of the floor of which is hinged at 23 and may be raised, when the door is open, to uncover a set of steps 24, which are pivoted at 25, and may be swung to service position by a hand lever 26 and connecting rod 27.

The door 20 is of the sliding type, and when closed fits snugly within the casing 28, its outer face being flush with the side wall 45 of the car body, thereby contributing to the streamline effect sought to be obtained in the car. The door, as shown, is of the arch form, its upper end being arcuate, the door opening being of corresponding

The door is supported and is movable in a channeled track, one section 29 of which is mounted in the upper face of the openable section 22 of the vestibule floor and connects directly with a section 30 extending along the car floor adjacent to the inner face of the side wall of the car. The track comprising the two sections 29, 30, is provided with two lateral extensions 31, 32, leading obliquely into the door opening and located one adjacent to each side thereof. Within suitable recesses in the bottom of the door, positioned directly above the ends of the track extensions when the door is closed, are a pair of anti-friction studs or rollers 33, preferably of the centrally swiveled caster variety, these rollers running in the track 29, 30, which in cross-section is of suitable form to receive them.

Similar means are provided for guiding the upper portion of the door in its opening and closing movements, and comprise a guide track 34, suitably supported by the side wall or framing of the car, as indicated in Fig. 3, and leading laterally from the door opening. The forward end of this track is provided with a lateral extension 35, leading toward the door casing. The door carries a guide stud 36, preferably of anti-friction type, and, as shown, being similar to the casters 33. This guide stud engages within the channel of the track 34, 35, and, the door being of the arch type, is located on its vertical median line.

The tracks and the disposition of the guide studs or rollers cooperating therewith are so relatively located that the top and bottom studs register with the lateral track extensions simultaneously. The upper guide stud being located intermediate of the two lower ones, cooperates with each to prevent a tendency to any turning movement of the door, and consequently as the upper stud and the forward lower stud enter the lateral track extensions with which they cooperate the rearward lower stud is drawn into the track extension 32, and the door is properly guided to its seat within the casing.

This arrangement also causes the forward guide stud or roller at the bottom of the door to pass the required lateral track extension 32 in closing.

As an additional safeguard against possible deflection of the forward roller from entering the track extension 32, an anti-friction roller 37 may be attached to the rearward side of the door frame for engaging the outer face of the door in the opening and closing movement.

Various changes in details may be made within

the scope of the invention, as defined in the appended claims.

I claim as my invention—

1. A railway car comprising a body having a door opening, a sliding door for closing the opening, a channel track for carrying the door and crossing the door opening and extending laterally therebeyond, adjacent the inner face of the car wall and having a pair of obliquely extending lateral channels adjacent the door opening, rollers connected with the lower margin of the door and running in the track, a guide track carried by the car body at the top of the door opening and extending laterally from a point intermediate of the side margins thereof, such track having a lateral extension at its forward end, and an element carried by the door and engaging in the last-named track. 5
2. A railway car comprising a body having a door opening, a sliding door for such opening, a supporting channel track extending substantially across the opening and along the inner face of the body wall and having a pair of lateral extensions, a pair of rollers carried by the door and spaced apart corresponding with the spacing of the lateral extensions, a track above the opening parallel with the lower track and extending from a point intermediate of the sides of the opening, the forward end of the track being inclined corresponding to the inclination of the lower track extensions; and a guide element carried by the door and engaging the upper track. 10
3. A railway car comprising a body having an arched door opening, a sliding door for closing the opening, a supporting track for the door and a guide track for the top of the door, both tracks extending along the inner face of the car wall, the supporting track having a pair of lateral extensions one adjacent each side of the opening and the guide track having a single lateral extension adjacent the vertical center line of the opening, and rollers carried by the door and engaging the tracks. 15
4. A railway car comprising a body having a door opening, a sliding door for such opening, a supporting channel track extending substantially across the opening and along the inner face of the body wall and having a pair of lateral extensions, a pair of rollers carried by the door and spaced apart corresponding with the spacing of the lateral extensions; a track above the opening parallel with the lower track and extending from a point intermediate of the sides of the opening, 20
- the forward end of the track being inclined corresponding to the inclination of the lower track extensions, and a guide element carried by the door and engaging the upper track. 5
5. A railway car comprising a body having a door opening and an upwardly swinging floor section extending into such opening, a sliding door for such opening, a track for the door extending across the named floor section and an extension of the track carried by a fixed portion of the body, 10 and a guide track for the top of the door. 15
6. In combination, a sliding door having a pair of track-engaging elements at its lower edge, a supporting track therefor, the track having lateral extensions for shunting the door into closed position, a guide track above the door having a single corresponding lateral extension, and a stud carried by the upper edge of the door for engaging the track and located intermediate of the side margins of the door. 20
7. In combination, a sliding door having a pair of track-engaging elements at its lower edge, a supporting track therefor, the track having lateral extensions for shunting the door into closed position, a guide track above the door having a corresponding lateral extension, and a stud carried by the upper edge of the door for engaging the track and located intermediate of the vertical lines through the first-named track-engaging elements. 25
8. In combination, a sliding door, a pair of tracks for carrying and guiding the door and located respectively at the top and bottom thereof, one of such tracks having two lateral extensions for shunting the door into closed position and the other having a single such extension forward of the vertical plane of the rearmost of said two extensions, and track-engaging elements carried by the door for cooperating with such lateral extensions. 30
9. In combination, a sliding door, a pair of tracks for carrying and guiding the door and located respectively at the top and bottom thereof, one of such tracks having two lateral extensions for shunting the door into closed position and the other having a single such extension, track-engaging elements carried by the door for cooperating with such lateral extensions; and means bearing against the door for holding the door against lateral movement until each track-engaging element is aligned with a lateral extension of its track. 40
10. In combination, a sliding door, a pair of tracks for carrying and guiding the door and located respectively at the top and bottom thereof, one of such tracks having two lateral extensions for shunting the door into closed position and the other having a single such extension, track-engaging elements carried by the door for cooperating with such lateral extensions; and means bearing against the door for holding the door against lateral movement until each track-engaging element is aligned with a lateral extension of its track. 45
11. In combination, a sliding door, a pair of tracks for carrying and guiding the door and located respectively at the top and bottom thereof, one of such tracks having two lateral extensions for shunting the door into closed position and the other having a single such extension, track-engaging elements carried by the door for cooperating with such lateral extensions; and means bearing against the door for holding the door against lateral movement until each track-engaging element is aligned with a lateral extension of its track. 50
